COMBINED WASHER AND EXTRACTOR

Gerald I. Cockerill, Cleveland Heights, and Ralph L. Archbold, Euclid, Ohio, assignors to The Apex Electrical Manufacturing Co., Cleveland, Ohio, a corporation of Ohio

Application October 19, 1946, Serial No. 704,482

10 Claims. (Cl. 68—23)

1 This invention relates to washing machines, more particularly to a novel valve means which forms part of the structure for balancing the rotating tub of a centrifugal drying type machine.

An object of our invention is to provide means to lubricate the rubber valve member during the washing cycle at which time the balancing features of the machine are not employed and the source of water under pressure to the valve is cut off. One method of accomplishing this object in a preferred embodiment lies in utilization of the water pressure accumulated in a hydraulically operated brake during the drying cycle, this water being made available for lubricating the balancing valve during the washing cycle.

Another object of our invention lies in the provision of safety means so that if the water pressure is cut off, the drying or spinning action of the tub automatically ceases. If a large unbalance were present and if no water were available to correct the unbalance there might develop an undesirable vibrating action in the machine. With a machine made in accordance with the invention, the tub is supported upon elongated shaft or sleeve means which may be employed to impart an agitating action to the articles within the tub or basket, and a rotating or spinning action to the tub for drying or extraction. A water balancing or water distributing valve is incorporated in the machine sensitive to lateral motion of the tub supporting means that occurs due to centrifugal unbalance of the tub and particularly the articles therein, which valve means distributes water to receptacles or pockets on the tub in such a manner as to lessen the unbalance whereby the tub is progressively balanced at the extraction operation.

Control apparatus for the machine likewise includes holding means, preferably in the form of a brake, connected to an extensible fluid motor and actuated by the pressure of liquid such as water used to wash the articles and balance the container. The action of the fluid motor is opposed by suitable means such as a spring, the arrangement being that the brake is released by fluid pressure and applied by the spring, and a source of fluid pressure is connected to both fluid motor and the balancing valve through the shut-off valve.

It is a feature of the invention that the mechanism is protected against excessive vibration due to unbalance in that the spinning action is automatically halted and the machine returned to washing when the source of fluid under pres-

sure is removed and the shut-off valve closed. This desirable object is attained by the aforesaid construction or its equivalent in that so long as fluid under pressure, such as water, is available in the apparatus the balancing valve and mechanism may function to balance the tub and the brake will be correspondingly released to permit spinning of the tub for extraction. Should the water supply fail during extraction, thereby rendering the balancing structure inoperative, the brake will be engaged to prevent spinning of the basket and obviate a generation of excessive forces due to unbalance of the articles in the basket.

2 Another object of the invention resides in insuring that the means that tends to prevent spinning of the tub, which is the brake actuated by a spring in the preferred embodiment of the invention, is not blocked from operation due to the presence of water or other liquid in the fluid motor and conduits. This is accomplished by providing a bleed aperture in the conduit system for unblocking the fluid motor and permitting engagement of the brake or equivalent means, which bleed aperture is preferably disposed at the balancing valve end so that the liquid that emerges therefrom bathes the valve and may act as a lubricant thereto during the ensuing operation of the device. These and other objects will be apparent to those skilled in the art as the following detailed description of a preferred embodiment of my invention proceeds.

In the drawings:

Fig. 1 is a cross sectional view of the washing machine showing the general association of the parts thereof that apply to the present invention;

Fig. 2 is a transverse section through the tub, in plan, showing the configuration of the balancing pockets and with parts broken away to show the configuration of the channels to direct water to the balancing pockets;

Fig. 3 is a transverse section through the tub taken on line 3—3 of Fig. 2;

Fig. 4 is an enlarged section through the balancing valve;

Fig. 5 is a fragmentary section showing the adjusting shims; and, Fig. 6 shows brake structure detail taken on 6—6 of Fig. 1.

The general arrangement of a form of washing machine embodying the present invention is shown in Fig. 1. The working parts are in housing H and supported by a plurality of legs I. The vertical pedestal member D is carried by the legs and supports the majority of elements in the

machine. Tub T is supported by the pedestal and may be given the washing action and the spinning action to be hereinafter described. The tub T is mounted in a water-tight container 2 and water may be pumped into the tub through the connection 3 by any convenient means. A detailed description of the water circulating means and several other features of control which may be employed will be found in the co-pending application of James B. Kirby, Serial No. 619,849, filed October 2, 1945.

Motor M drives a conventional V-belt or any convenient driving means to rotate the pulley 5. We prefer that there be a speed reduction in the V-belt drive of approximately three to one when using the standard 1750 R. P. M. motor in which case the pulley 5 will turn about 600 R. P. M. Pulley 5 drives a vertical hollow shaft 6, the lower end of which is supported in the pedestal by bearing 5a, and the upper end of which is connected to an upper driving fitting 7.

Fitting 7 mounts a bearing 40 to support an upper fitting 8. Fitting 8 carries a member 9, preferably an aluminum casting, that forms the central part of the tub. With this construction the vertical shaft 10 may drive the tub for drying through the universal joint U. The lower portion of shaft 10 is connected to a brake drum 11 which drum also supports centrifugal clutch shoes 12. The brake assembly, supported from the frame in any suitable manner, includes a brake band 13 contracted against the brake drum 11 by a spring 15 or the natural resiliency of the brake band 13, or both, and an operating bellows B or the like connected to the brake band 13 by a lever 14 of the first class, as disclosed in the aforesaid application, Serial Number 619,849, filed October 2, 1945. When water pressure is supplied to the bellows B the brake band 13 is held in released position and when no water pressure is supplied to the bellows B the spring 15 causes the brake band 13 to grip the drum 11, thereby preventing rotation of shaft 10 and thence of the tub T. Rotation of the pulley 5 and hollow shaft 6, however, is permitted which gives the tub its washing motion.

A source 20 of water under pressure may connect to a remotely controlled solenoid operated valve 21. When valve 21 is opened, water enters line 22 and releases the brake B against the spring pressure. Simultaneously, another line 23 conducts water under pressure to the balancing valve V. The controlling means is so arranged that the valve 21 is opened when the machine control is set for drying, so that the brake is released to permit the tub to turn and so that water is available for balancing.

The tub T has formed around its circumference a series of balancing pockets P and with each pocket there is an associated channel C for directing water from its point of release at the balancing valve V into the pockets. Fastening means 30 retain the sheet metal structure of the tub to the central supporting casting 9 and a plate 31 closes the lower ends of the channel C which plate may be fastened to the member 9 by means of screws 32. Apertures 33 may be provided in the tub in between the pockets in order to permit water to escape from the tub during the drying operation.

A more detailed view of the tub supporting structure appears in Fig. 3. The fitting 7 that is connected for rotation by the hollow sleeve 6 supports upper ball bearing 40 described previously, there being a retaining washer 41. The

upper fitting 8 has the extension 42 and is clamped to the tub casting 9 by means of a nut 43. A pin 44 provides a driving connection between fitting 8 and tub casting 9. The universal joint U has one yoke connected with the driving shaft 10 and the other with the upper fitting 8 so that the shaft 10 is always rotatably coupled to the tub. During the washing, when water pressure to brake B is cut off, brake band 13 clamps and holds shaft 10, and by means of universal joint U, the tub is prevented from rotation. However, it will be noticed that the axis of rotation of the ball bearing 40 and hence that of the tub itself is inclined to the vertical axis defined by shafts 6 and 10. Thus, when fitting 7 is rotated and shaft 10 and the tub are restrained from rotation as during the washing cycle, the tilted bearing causes the geometric axis of the tub to sweep over a conical path having its apex in the universal joint. The universal joint permits this action to take place even though the tub is held from rotation. The result is that any given point in the tub has a rapid rising or falling action and different parts 10 of the mass of water and articles in the tub T are reciprocated in a vertical direction with progressively different phases about the center.

To initiate the drying action, valve 21 is opened to connect water pressure from line 28 30 to lines 22 and 23. Now brake 13 releases shaft 10 for rotation and water under pressure is applied to the balancing valve V. During the initial portion of the drying cycle, the reaction of tub T against the wobble action caused by 35 rotation of sleeve 6 causes the tub to gradually assume the speed of the rotating hollow sleeve 6. At a predetermined speed of tub rotation, the centrifugal clutch member 12 carried by the brake drum 11 flies out to engage a clutch drum 40 12a mounted on the rotating pulley 5. Now shaft 10 is clutched to hollow shaft 6 so that tub T spins at the speed imparted to pulley 5. The structural details of the clutch structure are more fully described in the aforesaid pending application and form no part of the present invention.

With the tub spinning, if any unbalance is present, the tub supporting sleeve 6 tends to lean over in the general direction of the heavy side 50 of the tub. This brings balancing valve V into operation, details of which are clearly seen in Figs. 4 and 5 and claims to this valve unit are presented in my divisional application Ser. No. 200,044, filed December 9, 1950 entitled, "Balancing Valve for Combined Washers and Extractors." The pedestal supports a metal sleeve member 50 to which is bonded a rubber valve sleeve 51. The other element of the valve comprises an inner relatively non-resilient or metallic member 52 to which is fastened an upper water deflecting disc 53. Member 52 and rubber sleeve member 51 may be fastened together at their lower ends by means of a cup shaped member 54 bonded to the rubber and clamped to the inner sleeve member 52 by means of washer 55 and fastening means 56. An upper portion of the rubber member may be formed with one or more ribs 57 that engage and seal against the smooth tapered portion 58 formed on the inner 60 valve member 52. The action of the valve and the amount of water permitted to escape between the parts for a given unbalance can be adjusted by adding to and decreasing the number of shims 61 placed between the end of inner valve member 52 and the cup shaped member 54

bonded to the rubber member 51. For example, as each shim is removed, tapered part 58 is pulled further into the rubber valve and there is a tighter engagement between the two valve elements. The valve parts are arranged to provide an annular pocket 59 which connects to aperture 23a so that water may be introduced from line 23 for escape between the two valve parts. It can be seen that if there is any unbalance in the tub as it spins, the tub supporting sleeve 6 will tend to lean in the direction of the heavy area. This will tend to open up a small crack or orifice between the rubber ribs 57 and the tapered metal member 58 at an area generally placed 180° from the unbalanced area. Water under pressure can therefore escape between the parts of the light or high side of the assembly whereupon it is deflected by the disc 53 into channel C formed on the tub to eventually find its way into the water balancing pockets P at the periphery of the tub. Apertures 34 are provided to prevent the eventual filling up of the pockets whereupon no further balancing action would be possible. This action continues until the unbalance is corrected.

Due to the relatively smooth surface of the tapered part 58, it can be seen that continuous operation of the machine will produce very little wear on the rubber sealing ribs. Likewise, the arrangement of the ribs is such that rubber can flow in response to an unbalanced load and permit the parts to separate on the light side of the tub as described even though rubber itself is of a relatively high order of hardness. Thus a satisfactory valve action is obtained without sacrifice in the strength and durability of the rubber member.

When the washing action is initiated, the solenoid-operated valve 21 cuts off water pressure from source 20 to lines 22 and 23. When this happens, spring means are provided to apply the brake 13 and, at the same time, water from the bellows B of the brake is urged up through lines 22 and 23 and into pocket 59. Water in pocket 59 keeps the valve lubricated and minimizes the wear which might occur between member 58 and the rubber member 51 due to vibration during the washing action. In order to insure that the brake will not be hydraulically blocked, an orifice or restriction plug O is provided in passageway 62 above pocket 59 which plug has a small orifice 63 that permits a small amount of water to escape without draining the pocket 59. While the valve 21 is open water pressure from the line 20 is applied to the bellows 14 to maintain the brake disengaged and water is also supplied through the line 23 to keep the pocket 59 filled and to supply water to the balancing pockets when the rubber valve sleeve 51 opens. Throughout this part of the cycle and also during a time when the brake is being applied by the spring 15, forcing water from the bellows 14, a stream of water passes through the orifice 63 against the deflector 53 which maintains the upper surface of the valve sleeve 51 wet and insures lubrication of the valve even if the tub should be so well balanced that the rubber valve 51 does not open during a particular cycle of operation.

We contemplate that various modifications from the invention as illustrated may be made within the scope of the claims. Valve member 58 can be of metal or any material which is somewhat harder than the rubber sleeve 51. Likewise, it would be a mere reversal of the

parts to make the rubber member an inner member and to make the metal or non-resilient member the outer member of the valve assembly. We contemplate that member 51 may be made of any resilient material such as rubber, synthetic rubber or any suitable plastic material. The critical consideration in the valve construction lies in making the parts so that they will permit water to be expelled from pocket 59 into the tub when unbalance is present. We also contemplate that if no brake B is employed in the system, the orifice 63 or some similar means may be provided to supply lubricating water for the valve.

15 Although we have described the invention in connection with a washing machine wherein water is used as the balancing medium, it is contemplated that the arrangement is equally adaptable to a machine for dry cleaning articles by the use of a suitable liquid solvent such as carbon tetrachloride or the like, and in this instance, the solvent would also be employed as the balancing liquid. Also, the rubber would be replaced by a resilient compound, preferably synthetic, which would be unaffected by the particular liquid solvent employed.

These and other modifications may be made without departing from the spirit of the invention as defined in the appended claims.

30 Having thus described the present invention so that others skilled in the art may be able to understand and practice the same, we state that what we desire to secure by Letters Patent is defined in what is claimed.

35 What is claimed is:

1. In combination in a washing machine, a rotatable perforated tub having a plurality of water balancing pockets, means to spin said tub for drying, a hydraulic operator for said spin 40 means arranged to initiate spinning when water pressure is applied to the hydraulic operator, a valve assembly for directing water into said balancing pockets, said hydraulic operator means and said valve assembly being connected to a common source of water under pressure, and a cut-off valve in said pressure source whereby opening said cut-off valve initiates spinning of the tub and supplies water to said valve assembly for balancing the tub.

50 2. In combination in a washing machine, a rotatable tub having a plurality of water balancing pockets, means to spin said tub for drying, holding means to prevent spinning of said tub for washing, a hydraulic operator to release 55 said holding means, a valve assembly for directing water into said balancing pockets, said hydraulic means and said valve means being connected to a common source of water under pressure, and a cut-off valve in said pressure source 60 whereby opening said cut-off valve releases said tub for spinning and supplies water to said valve assembly for balancing the tub.

65 3. In combination in a washing machine, a rotatably mounted tub, first rotating means to agitate said tub for washing, second rotating means to spin said tub for drying, means whereby said first rotating means tends to turn said second rotating means and so spin the tub, holding means for said second rotating means to 70 prevent spinning of said tub during the washing operation, operator means actuated by water pressure to release said holding means to permit spinning of said tub for drying, water balancing means including a valve to balance said tub 75 when it is spinning, a source of water under

pressure connected to said balancing valve and to said operator means, and means on said operator means opposed to the action of water pressure thereon to engage said holding means whenever said source of water pressure is cut off, whereby said tub is restrained from spinning when no water for said balancing means is available.

4. In combination in a washing machine, a rotatably mounted tub, first rotating means to agitate said tub for washing, second rotating means to spin said tub for drying, means whereby said first rotating means tends to turn said second rotating means and so spin the tub, holding means for said second rotating means to prevent spinning of said tub during the washing operation, spring means tending to engage said holding means, operator means actuated by water pressure to release said holding means to permit spinning of said tub for drying, water balancing means including a distributing valve to balance said tub when it is spinning, a source of water under pressure connected to said balancing means and to said operator means, means to engage said holding means whenever said source of water pressure is cut off, and means to bleed water from said operator means to lubricate said distributing valve.

5. In combination in a washing machine, a rotatable tub having a plurality of liquid balancing pockets, means to spin said tub for drying, holding means to prevent spinning of said tub for washing, a hydraulic operator to release said holding means, a valve assembly for directing liquid into said balancing pockets, said hydraulic means and said valve means being connected to a common source of liquid under pressure, and a cut-off valve in said pressure source whereby opening said cut-off valve releases said tub for spinning and supplies liquid to said valve assembly for balancing the tub.

6. In combination in a washing machine, a rotatable perforated tub having a plurality of water balancing pockets, means to spin said tub for drying, a hydraulic operator for said spin means arranged to initiate spinning when water pressure is applied to the hydraulic operator, means for directing water into said balancing pockets, said hydraulic operator means and said water directing means being connected to a common source of water under pressure, and a cut-off valve in said pressure source whereby opening said cut-off valve initiates spinning of the tub and supplies water to said water directing means for balancing the tub.

7. In combination in a washing machine, a rotatable tub having a plurality of liquid balancing pockets, means to spin said tub for drying, holding means to prevent spinning of said tub for washing, a hydraulic operator to release said holding means, means for directing water into said balancing pockets, said hydraulic means and said water directing means being connected to a common source of water under pressure, and a cut-off valve in said pressure source whereby opening said cut-off valve releases said tub for spinning and supplies water to said water directing means for balancing the tub.

8. In combination in a washing machine, a rotatably mounted tub, a brake to hold said tub against rotation, means to agitate articles in said tub for washing with said brake engaged, means to spin said tub with said brake released for drying, operator means controlled by water pressure to release said brake, water balancing means including a means to distribute water to balance said tub when it is spinning, a source of water under pressure connected to said water distributing means and to said operator means, a cut-off valve in said source, and means opposed to the action of water pressure on said operator means to engage said brake whenever said source of water pressure is cut off, whereby said tub is held from spinning when no water for said distributing means is available.

9. In combination in a washing machine, a rotatably mounted tub, a brake to hold said tub against rotation, means to agitate articles in said tub for washing with said brake engaged, means to spin said tub with said brake released for drying, fluid motor means operable by water pressure to release said brake, water balancing means including a valve to distribute water to balance said tub when it is spinning, a source of water under pressure, a cut-off valve at said source, conduit means leading from said cut-off valve to said balancing valve and to said operator means, spring means tending to engage said brake whenever said cut-off valve is closed, and a restricted bleed orifice in said valve to prevent hydraulic blocking of said fluid motor means when said cut-off valve is closed.

10. In combination in a washing machine, a rotatable perforated tub having a plurality of water balancing pockets, means to spin said tub for extracting liquid therefrom, a hydraulic operator for said spin means arranged to initiate spin when water pressure is applied to the hydraulic operator, means for directing water into said balancing pockets, said hydraulic operator means and said directing means being connected to a common source of water under pressure, and a cut-off valve in said pressure source whereby opening said cut-off valve initiates spinning of the tub and supplies water to said directing means for balancing the tub.
